O. BANNER.

TURBINE.

APPLICATION FILED DEC. 27, 1911.

1,111,349.

Patented Sept. 22, 1914.

Inventor:

Otto Banner
by his attorney
Brown & Ward

UNITED STATES PATENT OFFICE.

OTTO BANNER, OF EASTON, PENNSYLVANIA, ASSIGNOR TO INGERSOLL-RAND COMPANY, OF NEW YORK, N. Y., A CORPORATION OF NEW JERSEY.

TURBINE.

1,111,349.

Specification of Letters Patent. Patented Sept. 22, 1914.

Application filed December 27, 1911. Serial No. 668,082.

To all whom it may concern:

Be it known that I, OTTO BANNER, a subject of the German Emperor, and resident of Easton, in the county of Northampton and State of Pennsylvania, have invented 5 a new and useful Improvement in Turbine-Engines, of which the following is a specification.

This invention consists in a horizontal 10 double flow turbine engine of the so-called action or velocity type and is particularly applicable to those engines where the speed renders it difficult to pass the motive fluid out through a single outlet.

15 This invention is especially well adapted for use in connection with low pressure turbine engines but is not limited to such use.

Practical embodiments of the invention 20 are represented in the accompanying drawings, in which—

Figure 1 is a view of the engine half in side elevation and half in longitudinal central vertical section showing one form of inlet, and Fig. 2 is a detail section showing a 25 modified form of inlet.

The engine shaft is denoted by 1, the 30 blade wheels which are fixed thereto by 2, and their row of blades by 3. The casing is provided at its ends with chambers 4 and 5 communicating with their outlets 6 and 7.

In Fig. 1 the casing is shown as provided 35 with a transversely divided chamber 8, 9, communicating with the divided intermediate inlet 10, 11, and having the oppositely arranged rows of nozzles 12, 13.

In Fig. 2 the chamber 14 is shown as undivided and its inlet 15 as undivided, the oppositely arranged nozzles 16, 17, leading 40 from the said undivided inlet chamber. The transverse partitions carried by the casing and alternating with the blade wheels are denoted by 18 and their nozzles by 19. The 45 bearings for the engine shaft are located at the opposite ends of the casing and are preferably divided in a horizontal plane co-incident with the axis of the shaft to form upper and lower members 20, 21, and 22, 23, respectively.

The casing is preferably divided in a horizontal 50 plane co-incident with the axis of the shaft and in transverse vertical planes to form upper members 24, 25, 26; and lower

members 27, 28, 29, the lower members 27 and 29 being provided with brackets 30, 31, for supporting the casing and the members 55 25, 28, forming the ring which contains the intermediate inlet chamber. The partition 32 which divides the inlet chamber may be formed integral with the ring members or attached thereto in any manner. 60

Valves 33, 34, are shown in Fig. 1 for independently controlling the admission of the motive fluid to the inlet chambers 8, 9, and a valve 35 is shown in Fig. 2 for controlling the admission of motive fluid to the single 65 inlet chamber 14.

In the accompanying drawings, the turbine engine is shown as provided with four stages upon each side of the motive fluid inlet chamber and the wheels as having single 70 rows of blades but the number of stages and the number of rows of blades may be varied as desired.

It will be seen that in a turbine engine constructed as herein set forth, the motive 75 fluid will enter the turbine engine intermediate its ends and will pass therefrom toward the opposite ends of the engine where it will be permitted to escape through separate outlets thus permitting a very ready 80 and rapid exhaust of the motive fluid.

In that arrangement in which the inlet chamber is divided, the admission of the motive fluid may be so controlled as to permit the same to be admitted to one set of 85 wheels while the other set of wheels is turning idly up to a predetermined load and then permit the admission of the motive fluid to the idly running set of wheels. 90

What I claim is:—

1. A turbine engine comprising a shaft, two sets of blade wheels thereon arranged to drive the shaft in the same direction, a casing, two sets of nozzles carried thereby, outlets at the ends of the casing, a divided 95 inlet intermediate the two sets of blade wheels and nozzles and means for controlling the admission of the motive fluid to either one or both sides of said divided inlet for driving either of the two sets of blade 100 wheels or both sets of blade wheels.

2. A double flow turbine engine having outlets at its ends and an intermediate inlet comprising a divided ring having nozzles

through its walls arranged in position to direct the fluid outwardly to the two elements of the engine, and means for controlling the admission of the motive fluid to either one or both sides of said divided ring.

In testimony, that I claim the foregoing as my invention, I have signed my name in

presence of two witnesses, this 23 day of Dec., 1911.

OTTO BANNER.
